H. C. EBEL,
DRYING APPARATUS,
APPLICATION FILED AUG. 10, 1915.

Patented Mar. 21, 1916.

UNITED STATES PATENT OFFICE.

HERMANN CHRISTIAN EBEL, OF HANOVER, GERMANY.

DRYING APPARATUS.

1,176,706.

Specification of Letters Patent. Patented Mar. 21, 1916.

Application filed August 10, 1915. Serial No. 44,829.

To all whom it may concern:

Be it known that I, HERMANN CHRISTIAN EBEL, a subject of the King of Prussia, residing at 29 Asternstrasse, Hanover, in the 5 German Empire, have invented certain new and useful Improvements in Drying Apparatus, of which the following is a specification.

My invention relates to drying apparatus 10 and particularly to apparatus for drying salt and the like easily affected crystals or other substances. Apparatus hitherto used for drying such substances consist of an upright casing heated through its side 15 walls. In such apparatus the substances to be treated are fed into the apparatus from above and pass through a series of superposed through-like carriers which revolve about their longitudinal axis and cause the 20 substances under treatment to gradually drop from carrier to carrier and thereby come in contact with the drying air ascending. Finally, the substances are discharged at the foot of the apparatus.

25 The object of my invention is to provide an improved heating system for drying apparatus of such construction.

A further object is to improve upon the 30 construction and the disposition of the rotating carriers.

Hitherto, drying apparatus of the described type have been heated by a system of indirect heating in which the heat carrying gases are caused to pass through an inclosed 35 space which is traversed by the tubes through which the drying air is led before entering the drying apparatus. In this manner the air conducting tubes are heated by the heating gases surrounding them and transfer the 40 heat to the air passing through the tubes. Such a system of heating tubes has been applied, for instance, with a well known apparatus in a separate brick-built chamber in front of the drying shaft. Another apparatus 45 has become known having a separate chamber besides the drying shaft which chamber is traversed by a system of steam pipes while the air to be dried is caused to flow through the heating chamber and 50 around the steam pipes and thereafter enter the drying shaft.

According to my invention the heating pipes for admitting the drying air are placed standing side by side in succession 55 along the outside of the longitudinal side walls of the driving shaft and are inclosed

in chambers through which the heating fluid (flue gas, steam or the like) are caused to flow. Such air admitting tubes may be provided in any desired number in conformity 60 with the required heating surface. By this arrangement of the heating device a favorable exploitation of the heat is secured since not only the air admission tubes are heated by the heating fluid but simultaneously the 65 side walls of the drying shaft through which the substances to be dried are passing. Another effect secured by this arrangement lies in the fact that the drying air, in doing its work in the drying shaft, is enabled to continually recuperate the heat it is losing during the drying process, from the heat radiated by the walls of the drying shaft. Thus, a uniform temperature is maintained in the drying shaft and this is a very important 75 factor in treating easily affected substances, especially such as, for instance salt, to secure a stable coloration of the same.

As regards the conveying carriers, these consist of shallow double troughs placed one 80 below the other in such a manner that the circumferential traveling paths of two adjacent troughs cross each other. Such a construction and arrangement of the conveying means effects a smooth downwardly 85 directed sliding movement of the conveyed substances and prevents damaging the substances while undergoing the sliding movement. Another result of this arrangement of the conveying carriers is the reduced 90 height of the whole apparatus; the closely disposed conveying carriers which are engaging each other with interior sliding surfaces turn the substances to be dried over more effectively and in a shorter apparatus. 95 Thus, the drying effect is obtained within a shorter way of travel as in apparatus previously known, wherein the construction of the carriers, which, for instance, showed the form of hollow shafts provided with ribs, rendered it impossible to have the traveling paths of two adjacent carriers cross each other; hence, the material to be conveyed through the apparatus had to drop a considerable distance to reach the next carrier 100 below, whereas in the novel device according to my invention the material is only subjected to a smooth sliding movement produced in consequence of the shallow double trough form of the conveyors. In apparatus as they have been known hitherto, there is always the possibility that sub-

stances which become easily incrusted and are of a delicate nature, like salt, will be arrested and baked within corners between the ribs or rib supporting means; this possibility is obviated through the improvements according to my invention.

An embodiment of my invention is illustrated in the accompanying drawings, in which—

10 Figure 1 shows in elevation a cross section along the line A—B of Fig. 2. Fig. 2 is a sectional side elevation, partly along the line C—D, and partly along the line E—F, in Fig. 1. Fig. 3 shows details of the preceding figures on an enlarged scale.

The apparatus consists of an upright casing which is narrow and comparatively long, and is composed of a bottom 2, a cover 1, two end walls 3 and 4, and the side walls

20 5 and 6. In front of both side walls 5 and 6 and extending to the entire height of the same there are disposed tubes 7 shown inclosed by outer shells 8 and 9. The tubes 7 are open at their upper ends which terminate

25 within the chamber formed between the outer walls 8 and 9 and the walls 10, 11 arranged at some distance from the former. Preferably and in accordance with the amount of the heating surface required the

30 tubes 7 are provided side by side and in succession along the entire length and height of the apparatus and terminate with their lower ends within the drying shaft. The heating gases enter through the tubes 12

35 the heating chambers inclosed by the walls 5, 6 and 8, 9 and above and below by the plates 13, leaving the chamber at the upper end through the tubes 14. While passing through these chambers the heating gases

40 are imparting heat to the tubes 7 and the walls 5, 6 and 8, 9. The drying air entering into the spaces 16 intermediate the walls 8 and 10, and 9 and 11 respectively, as indicated by arrows 15 becomes primarily

45 heated by the heat radiating from the walls 8 and 9, and passes then through the tubes 7 in which the air is further heated within the spaces 18 intermediate the walls 5 and 6, and 8 and 9, respectively. Finally, the air

50 enters the shaft 19 after having been increased to the highest temperature admissible by the heating gases coming directly from the heat generator and entering at this region the spaces 18 through the flues 12.

55 On the way upward through the drying shaft from which the air escapes through the apertures 20, the heat initially carried by the air and used up in the drying process is being continually recuperative from the

60 heat radiation of the inner side walls 5 and 6. By means of the partition walls 21 and 22 within the heating chambers the heating gas, or exhaust steam, is given a positive guidance.

65 The substances to be dried are fed into

the apparatus through the tube 25 into the distributer 26. Within the casing of the drying apparatus there are conveying carriers 27 which consist of pairs of oppositely disposed concave dishes 28 which are connected at their edges by means of pairs of convex plates 29. At both ends the conveying carriers are provided with circular plates 30. The carriers are fixedly mounted upon shafts 27^a supported in suitable bearings in the end walls 3 and 4. The shafts 27^a are provided with toothed wheels 31 at their extremities. As is shown in Fig. 1, each two adjacent carriers are disposed relatively toward each other in such a manner that when the dishes of one carrier are standing horizontally the dishes of the other carrier have assumed a vertical position extending with one end into the concavity of one dish of the horizontal carrier, and vice versa. The paths of movement of each two adjacent dishes are thus crossing each other. Furthermore, each two adjacent carriers are revolving in opposite directions; thereby, the substance undergoing treatment is slowly passed on from carrier to carrier and is constantly being turned over, thus enabling the drying air entering the drying shaft 19 at the foot and ascending to the escapes 20, to penetrate the substance intimately in all its layers and parts.

As will be seen upon reference to Fig. 3, the carriers may be provided with clearing devices serving to clear the dishes, while revolving, of substances tending to become easily incrusted. Such clearing devices may consist of brushes 32 made of steel or other suitable material, which brushes may be mounted upon the convex plates 29 in such a manner that they sweep, during rotation, the dishes of adjacent carriers. Instead of brushes 32, resilient cushions 33 may be used, or elastic scraping plates, as illustrated at 34 (Fig. 3).

As has been described above, the conveying carriers may be operated so as to cause two adjacent carriers to rotate in opposite directions and in such a manner that the dishes of one carrier have arrived in a horizontal position when the dishes of the other carrier are standing upright, as illustrated in Fig. 3.

I do not limit myself to any particular means of rotating the dishes or the order in which they are rotated.

Having thus described my invention, what I claim is:

1. In a hot air drying apparatus, the combination of a drying shaft, having conveying carriers revolvably mounted therein, of means for heating the drying air and the drying shaft, said means comprising heating chambers adjoining the drying shaft and separated from same only by its side walls, a system of air conveying tubes placed so

as to traverse said heating chambers and terminating in the drying shaft at the foot of the latter, inlets and outlets in the heating chambers for the heating fluid caused 5 to flow through said heating chambers, and air conduits leading to the air admission ends of said air conveying tubes.

2. In a hot air drying apparatus, the combination of a drying shaft, having conveying carriers revolubly mounted therein, of means for heating the drying air and the drying shaft, said means comprising heating chambers adjoining the drying shaft and separated from same only by its side walls, 10 air admission chambers above said air heating chambers, a system of air conveying tubes placed so as to traverse said heating chambers from said air admission chambers downward and terminating in the drying 15 shaft at the foot of the latter, inlets and outlets in the heating chambers for the heating fluid which is caused to flow through said heating chambers, partition walls within said heating chambers placed so as to 20 guide the heating fluid in a zig-zag course, and air conducting channels extending over the outside walls of said heating chambers, said air conducting channels being open at their lower ends and terminating in said air 25 admission chambers.

3. In a hot air drying apparatus, the combination of a drying shaft, a system of superposed conveying carriers therein, each conveying carrier consisting of a pair of oppositely curved dishes interconnected by a pair of concave longitudinal plates and circular end plates and being fixedly mounted upon a shaft revolubly mounted within said drying shaft, with means for 35 heating the drying air and the drying shaft, said means comprising heating chambers adjoining the drying shaft and separated from same only by its side walls, air admission chambers above said air heating chambers, 40 a system of air conveying tubes placed so as to traverse said heating chambers from said air admission chambers downward and terminating in the drying shaft at the foot of the latter, inlets and outlets in the heating 45 chambers for the heating fluid which is caused to flow through said heating chambers, partition walls within said heating chambers placed so as to guide the heating fluid in a zig-zag course, and air conducting channels extending over the outside walls of said heating 50 chambers, said air conducting channels being open at their lower ends and terminating in said air admission chambers.

55 4. In a hot air drying apparatus for easily affected substances, the combination of superposed conveying carriers, each of which

consists of a pair of oppositely curved dishes interconnected by a pair of concave plates and circular end plates, shafts mounted 65 within the drying apparatus and carrying said conveying carriers, said shafts being adapted to be revolved from outside the drying apparatus and thereby to rotate said conveying carriers, the superposed carriers 70 being arranged relatively to each other in such a manner that the path of movement of one carrier crosses the path of movement of each adjacent carrier, whereby the substance to be conveyed through the apparatus 75 is given a short smooth sliding movement.

5. In a drying apparatus, the combination of an upright casing, a system of superposed conveying carriers therein, each conveying carrier consisting of a pair of oppositely 80 curved dishes interconnected by a pair of concave longitudinal plates and circular end plates, shafts revolubly mounted within said casing and having said conveying carriers fixedly mounted thereon, means for revolving 85 said shafts, resilient scraping means projecting from said longitudinal connecting plates of the carriers so as to sweep during rotation the dishes of the adjacent conveying carriers, means for heating the drying fluid and 90 said casing, said means comprising heating chambers directly adjoining said drying casing and separated from same only by its side walls, air admission chambers above 95 said air heating chambers, a system of air conveying tubes placed so as to traverse said heating chambers from said air admission chambers downward and terminating in said drying casing at the foot of the latter, inlets and outlets in the heating chambers for 100 the heating fluid which is caused to flow through said heating chambers, partition walls within said heating chambers placed so as to guide the heating fluid in a zig-zag course, and air conducting channels extending 105 over the outside walls of said heating chambers, said air conducting channels being open at their lower ends and terminating in said air admission chambers.

6. In a hot air drying apparatus, a drying shaft, a system of superposed conveying carriers each carrier consisting of a pair of oppositely curved dishes interconnected by a pair of concave longitudinal plates revolubly mounted within said drying shaft with 110 means for heating the drying air, substantially as described.

In testimony whereof, I affix my signature in presence of two witnesses.

HERMANN CHRISTIAN EBEL.
